UNITED STATES PATENT OFFICE.

ORANGE O. OZIAS, OF DAYTON, OHIO.

DESIGN FOR A SCALE BASE-PLATE.

SPECIFICATION forming part of Design No. 33,825, dated January 1, 1901.

Application filed December 4, 1899. Serial No. 739,201. Term of patent 14 years.

To all whom it may concern:

Be it known that I, ORANGE O. OZIAS, a citizen of the United States of America, residing and having my post-office address in Dayton, in the county of Montgomery and State of Ohio, have invented and produced a certain new and original Design for a Scale Base-Plate; and I hereby declare that the following is a clear, full, and exact description thereof, reference being had to the accompanying drawing, in which like numerals refer to like parts.

The figure in the drawing illustrates a perspective view of a scale base-plate formed in accordance with my invention and design.

The leading or material feature of my design consists of a circular ring having the arms extending toward its center and a circu-

lar track upon one face of said ring and projections upon the opposite face of said ring.

In said drawing, 10 represents the ring. 11 represents the arms extending toward its center. 12 represents the circular track upon one face of said ring 10. Upon one side of 25 said base-plate opposite said track 12 are the projections 14, extending from said ring 10 at a point adjacent the meeting-points of ring 10 and arms 11.

What I claim is—

The design for a scale base-plate, substantially as shown and described.

In witness whereof I have hereunto set my hand this 23d day of November, 1899.

ORANGE O. OZIAS.
